UNITED STATES PATENT OFFICE

102,313

DESIGN FOR A SPECTACLE FRONT

Frederick R. Bishop, North Attleboro, Mass., assignor to The Bishop Company, North Attleboro, Mass., a corporation of Massachusetts

Application June 27, 1936, Serial No. 63,524

Term of patent 7 years

To all whom it may concern:

Be it known that I, Frederick R. Bishop, a citizen of the United States and a resident of North Attleboro, county of Bristol, and Commonwealth of Massachusetts, have invented a new, original, and ornamental Design for a Spectacle Front, of which the following is a specification, reference being had to the accompanying drawing forming a part thereof, in which Fig. 1 is a front elevation of a spectacle front showing my new design; Fig. 2 is a top plan view; and Fig. 3 is a partial end view thereof.

The essential feature of my design resides in a spectacle front having arms that extend from the centers of the upper portions of the lenses along and just below and behind the peripheries of the said lenses, so as to be visible therethrough along the said peripheries.

I claim:

The ornamental design for a spectacle front substantially as shown and described.

FREDERICK R. BISHOP.
